UNITED STATES PATENT OFFICE

DAVID S. JACOBUS, OF JERSEY CITY, NEW JERSEY, ASSIGNOR TO THE BABCOCK & WILCOX COMPANY, OF BAYONNE, NEW JERSEY, A CORPORATION OF NEW JERSEY

ECONOMIZER

Application filed May 4, 1925. Serial No. 27,637.

My present invention relates to steam boiler economizers and particularly to the type in which tubes may be replaced readily.

My invention will be best understood 5 from the following description and the annexed drawings of an illustrative embodiment of my invention in which Fig. 1 is a side view of a part of an economizer in which the tubes extend across the gas flue and are 10 connected to headers at either end and at opposite sides of the flue; Fig. 2 is a view of Fig. 1 looking from the bottom of that Figure; Fig. 3 is a section on line 3—3 of Fig. 1, with the supporting plate omitted; Fig. 15 4 is a section on line 4—4 of Fig. 1, and Fig. 5 is a view of a part of the side view of the economizer, showing a modification.

Like reference characters indicate like 20 parts throughout the drawings.

In the illustrative embodiment, the tubes 10 extend across a gas pass and are arranged in rows, with the tubes in successive rows in 25 staggered relation. Headers 11 are single long boxes to which each tube of a row is connected. Headers 12 are relatively small boxes to which, in the illustrative embodiment, two tubes of each of two adjacent rows are connected, the headers 12 being arranged as shown best in Fig. 3. Elliptical hand- 30 holes are provided in each header 11 and 12 by which each of a group of four tubes may be cleaned through a single handhole, the headers being made deep enough to permit this. The outlines of the handholes are 35 shown in dotted lines in Figs. 3 and 4. While they can be made large enough to permit the cleaning of the tubes, a tube cannot be removed through them unless the tube can be turned at a considerable angle, which cannot 40 always be done. The handholes are covered by the usual handhole fittings 13.

Vertical plates 14, 14 suspended from above in any suitable manner, support tubes 10, being located adjacent the headers. Openings 45 15 in plates 14 surround the tubes 10, the openings being considerably larger than the outside diameter of the tubes and the tubes contacting with the lower walls of the holes and supported thereby.

If a tube 10 is to be removed, the ends of

all the tubes in the header 12 to which that tube is connected will be reduced in diameter so that the header can be removed from all the tubes of the group without injuring them. The tube to be removed will then be cut from 55 the opposite header 11 and a new tube inserted. The header 12 will then be replaced and the tube ends expanded into it. The tube to be removed may be drawn straight out through the space provided by the removal 60 of the header 12, or, in event there is not room enough outside the economizer for this, then it may be removed by angling it out through the side of the economizer, the holes 15 being made large enough to permit this 65 angling. The plates 14 serve to hold the tubes 10 in proper relation while the header 12 is removed.

By making the one set of headers in small 70 sections, it is obvious that a tube may be removed and replaced with very little difficulty since only a small header need be removed.

If the exteriors of the economizer tubes are to be washed with water, the spaces between the plates 14 and the headers may be 75 filled with a waterproof material, as indicated at 16 in Fig. 5, such material preventing the water flowing through the openings 15.

The arrangement which I have shown is 80 merely illustrative and the embodiment of my invention may be widely varied.

I claim:

1. In a device of the class described, oppositely disposed headers connected by a plurality of tubes, and perforated plates disposed between the headers with the tubes passing through the perforations, whereby the plates support the tubes and headers, said perforations being substantially larger 85 than the tubes supported therein and the tubes supported by the lower walls of the holes for the purpose set forth.

2. In a device of the class described, a plurality of groups of tubes, a continuous header connecting the tubes at one end thereof, and a plurality of relatively short headers disposed at the other end of said tubes and each connected to a group thereof.

3. In a device of the class described, a plu- 100

rality of groups of tubes, a continuous header connecting the tubes at one end thereof, a plurality of relatively short headers disposed at the other end of said tubes and each connected to a group thereof, and perforated plates disposed between the continuous headers and the plurality of short headers with the tubes passing through said perforations and supported by the walls of said perforations, whereby the plates support the tubes and headers.

4. In a device of the class described, oppositely disposed headers connected by a plurality of tubes, plates disposed between the 15 headers and adjacent to the respective headers, said plates having perforations therethrough in which the tubes are disposed, and waterproof material disposed between each plate and the adjacent header.

5. In a device of the class described, a plurality of tubes extending across a gas pass, connections between the ends of certain tubes on at least one side of said pass, and a plate disposed adjacent said connections and 25 having perforations substantially larger than said tubes, said tubes passing through said perforations and supported by the walls thereof.

6. In a device of the class described, a 30 plurality of tubes extending across a gas pass, connections between the ends of certain tubes on at least one side of said pass, a plate disposed adjacent said connections and having perforations through which the tubes 35 pass, and water proof material disposed between said plate and said connections and surrounding said tubes.

DAVID S. JACOBUS.

CERTIFICATE OF CORRECTION.

Patent No. 1,747,671.

Granted February 18, 1930, to

DAVID S. JACOBUS.

It is hereby certified that error appears in the printed specification of the above numbered patent requiring correction as follows: Page 1, lines 88 and 89, claim 1, strike out the words and comma "whereby the plates support the tubes and headers,"; and that the said Letters Patent should be read with this correction therein that the same may conform to the record of the case in the Patent Office.

Signed and sealed this 18th day of March, A. D. 1930.

M. J. Moore,
Acting Commissioner of Patents.
